UNITED STATES PATENT OFFICE

106,149

DESIGN FOR AN ANTENNA FOR AUTOMOBILE RADIOS

Edward L. Schiavone, Washington, D. C.

Application August 2, 1937, Serial No. 70,805

Term of patent 3½ years

To all whom it may concern:

Be it known that I, Edward L. Schiavone, a citizen of the United States, residing at Washington, in the District of Columbia, have invented a new, original, and ornamental Design for an Antenna for Automobile Radios, of which the following is a specification, reference being had to the accompanying drawing, forming a part thereof.

Figure 1 is a side view of the antenna of my new design.

Figure 2 is a top view of my antenna.

Figure 3 is a front view of the antenna.

I claim:

The ornamental design for an antenna for automobile radios, as shown.

EDWARD L. SCHIAVONE.
